ABSTRACT

The invention relates to a liquid-cooled transformer winding, preferably a disc winding, of the type in which the coolant is led through cooling tubes which are arranged in the winding simultaneously with the manufacture of the winding. The cooling tubes are arranged in only some of the winding discs, called cooling discs, and these cooling discs are preferably evenly distributed within the winding.

LIQUID-COOLED TRANSFORMER WINDING

has

This is a continuation of application Serial No. 403,491, filed Oct. 4, 1973, now abandoned.

BACKGROUND OF THE INVENTION**1. Field of the Invention**

The invention relates to direct liquid-cooling of transformer windings.

2. The Prior Art

In direct liquid-cooling of transformer windings the required length of the cooling tubes will be very large if the cooling tube is to follow the conductor for its entire length. This applies particularly to high-voltage windings, where the number of turns can be very great, in many cases over a thousand.

Furthermore, it is unrealistic to have only one input and one output because of the great length of the cooling coil which may be several thousand metres long. It is then necessary to have either a very high pump pressure to feed through a sufficient amount of liquid, or a very large cooling tube area, and this causes a disastrous decrease in the fill factor of the winding. A division into a number of preferably parallel cooling circuits is therefore necessary in practice. In this connection the problem arises of being able to arrange inlets and outlets for the coolant in a simple and practical manner, while at the same time the length of the cooling tube must be limited, both in view of the cost of the cooling tubes and in view of the fill factor of the winding.

SUMMARY OF THE INVENTION

The present invention aims at a solution to the above problem with direct liquid-cooling of transformer windings, preferably disc windings of the type in which the coolant is led through cooling tubes which are arranged in the winding simultaneously with the manufacture of the winding.

The particular characteristics of the invention are that a disc winding is provided with cooling tubes which are arranged in the windings during the manufacture thereof, the cooling tubes being arranged only in some of the winding discs, these cooling discs being evenly distributed within the winding. Furthermore, the invention contemplates a continuous member forming a part of the disc, parts of this member in some of the discs being hollow and providing a cooling passage while those in other discs are solid.

BRIEF DESCRIPTION OF THE DRAWINGS

In the accompanying drawings FIG. 1 shows a vertical section through part of the winding, FIG. 2 shows part of the cooling conductor and FIG. 3 shows a cross-section through two discs, one disc being manufactured.

DESCRIPTION OF THE PREFERRED EMBODIMENTS

The conductor bundle which is used in the manufacture of the winding in the example of the invention which will now be described have five solid conductor parts *a*, *b*, *c*, *d* and *e* and a cooling tube *f*. Of these, *a*, *b* and *c* are normal copper conductors, each one being drawn from a coil in the manufacture of the winding, whereas the parts *d* and *e* and the cooling tube *f* are joined to each other and connected to form a cooling

conductor which is manufactured beforehand. As is clear from FIG. 2, the cooling conductor comprises a through part *d* of the same type as *a*, *b* and *c* and also part *e* which, together with the four previously mentioned parts *a*, *b*, *c* and *d*, is included in the discs which lack cooling. In those discs in which cooling is arranged part *c* is replaced by cooling tube *f*, and at the beginning and end of the cooling tube part *c* and cooling tube *f* are joined by means of soldering at 1. The length of 10 the cooling tube *f* and the conductor part *c* and the location of the joints 1 are calculated beforehand based on information about the diameter of the winding, the number of turns per disc, and so on. In the manufacture of the cooling conductor inlets 2 are arranged at both 15 ends of the cooling tube and outlet 3 is positioned in the centre of the cooling tube. The cooling conductor is wound up on its own coil and is wound on together with parts *a*, *b* and *c*.

The winding is assumed to be manufactured in 20 known manner with the discs wound alternately from the inside outwards and from the outside inwards, respectively. When changing from one disc to another permutation of the conductor parts takes place so that the outermost part in one disc will be the innermost part in the next disc. It is thus clear from FIGS. 1 and 25 3 that in disc A the cooling conductor with its cooling tube *f* lies farthest in, but after four turns, when the disc A is completed, permutation takes place in connection with the transition from disc A to disc B so that in this 30 the cooling conductor with the cooling tube *f* has an outermost position. When disc B is finished the transition to disc C is made with permutation of the conductors so that discs A and C will be the same.

With reference to FIG. 3, the cooling conductor in 35 disc A according to FIG. 2 is made in such a way that during the part of the innermost turn when the permutation from the immediately preceding turn (not shown in the Figure) is finished, the cooling tube lies farthest in. At this very part the cooling conductor changes 40 from the conductor part *c* to the cooling tube *f* with an inlet 2, seen at the top or bottom of FIG. 2. The inlet 2 on the cooling tube *f* will thus be located on the inside of the winding. After four turns the disc A is completed and the permutation into disc B, starting with the conductor part *a*, begins. After almost another turn the 45 permutation is finished and the cooling tube *f* is farthest out. Then the outlet 3 will be accessible and will therefore be placed on the outside of the winding. After another four turns the disc B is finished and the conductor 50 bundle has proceeded and formed the innermost turn in disc C. Again the cooling tube is at the inmost position with the other inlet 2 on the inside of the winding.

The part of the winding disc where the cooling tube 55 is accessible, either on the inside of the winding, as in disc A, or on the outside of the winding as in disc B, is a few decimetres in size, depending on the diameter of the winding and on the permutation being carried out evenly distributed along the entire turn or only part thereof. If the permutation is evenly distributed said 60 distance, with five parallel conductor parts, as in the case shown, will be one fifth of the circumference. If the average diameter of the winding is 1.5 metre said distance will be about 1 metre. In that case the arrangement according to FIG. 2 is possible, i.e. placing a T-tube on the cooling tube and providing a common outlet for two discs or providing separate inlets and outlets that is connections to the outside for each disc. The 65

term "cooling discs" as used herein is intended to designate discs such as those shown which have cooling tubes forming part of the windings thereof.

As the conductor part *c* ceases when the cooling tube starts, the cooling tube may work as conductor part if it consists of electrically conducting material. This will lead to the area of the total conductor area being somewhat smaller in the cooling discs, but on the other hand the cooling is better there.

A transformer winding manufactured according to the example shown will thus have a number of cooling discs preferably fairly evenly distributed in the winding and suitably arranged two and two, as illustrated in FIG. 1. The inlets of the cooling tubes are arranged on the inside of the winding and the outlets on the outside or vice versa. Inlets as well as outlets are connected to common feeder tubes at the sides of the winding, thus making the cooling tubes parallel-connected.

Because of the great flexibility with regard to the number and positioning of the cooling discs, there are virtually unlimited possibilities of arranging cooling discs in the winding, thus providing the desired cooling

everywhere in the winding. It is possible, for example, to put in an increasing number of cooling discs counting from below and upwards towards the winding top where the highest temperature prevails.

I claim:

1. Liquid-cooled transformer winding of the disc type, in which a plurality of adjacent discs are each formed of a plurality of parallel conductor parts of the same cross-sectional width wound spirally in a plurality of turns, a majority of said conductor parts being solid, at least one of the conductor parts being hollow and comprising a tube for a cooling medium, said tube forming at least a portion of the innermost coil of a first of said discs, being transposed at the outside of the 15 winding to form at least a portion of the outer coil of the second adjacent disc and being further transposed at the inside of such second, adjacent disc to form at least a portion of the inner coil of the third, next adjacent disc, said tube portions having openings thereinto for ingress and egress of cooling fluid from outside the winding.
